ROTARY SWIVEL

Application filed June 23, 1928. Serial No. 287,874.

This invention relates to an elevator hanger and hitch by means of which drill pipe, tubing, sucker rods, and so forth, are handled in a well.

5 An object of our invention is to eliminate the hook and elevator links which are usual and well-known in structures of this character heretofore in use.

Another object is to provide an elevator 10 hanger and hitch which can not be uncoupled in event that the pipe or the like should become temporarily stuck in the hole. In running pipe, or the like, into the hole due to the constructions in the casing, or 15 curvatures, or other impediments, the pipe will stop momentarily and the hook will continue to descend, resulting in said hook disengaging the elevator links, and when the pipe frees itself it will fall into the hole resulting in various serious dangers. An advantage of our construction is that this danger will be overcome.

A further object of our invention is to eliminate the tangling of the swivel in the 20 elevator links by reason of the pipe, or the like, swinging to one side in the derrick, and if the blocks continue to descend the pipe will extend through the links and become entangled therein.

25 A further advantage of our construction is to provide an elevator hanger and hitch which has great strength and is not so liable to break under strain.

In the drawing:

25 Fig. 1 is a fragmentary side elevation of our elevator hanger and hitch.

Fig. 2 is a fragmentary longitudinal sectional view of the swivel bar.

40 Fig. 3 is a fragmentary side elevation of the swivel and suspending yoke.

Fig. 4 is a fragmentary side elevation of the elevator suspending link.

Referring more particularly to the drawing; the numeral 1 indicates a U-shaped bale 45 which is pivotally secured to a collar 2, which collar is slidably mounted on a pin 3 rising from a head 4. The collar 2 bears against a spring 5 and a thrust-bearing 6 is provided on the top of the pin 3 against 50 which the spring bears so that the collar is

freely rotatable on the pin. This spring and thrust bearing are of usual and well-known design and the details thereof form no part of this invention.

If desired, the spring, thrust bearing and 55 associated parts can be eliminated and an ordinary collar can be substituted therefor, all of which construction is usual in swivel hooks. The bale 1 is secured to the travelling blocks hung in the derrick by means of the 60 bale which extends from the bottom of the blocks. (The blocks and bale are not shown.)

A pair of arms 7, 8 extend outwardly from the head 4 and a pin 9 extends through the 65 head and the arms. A pair of elevator links 10, 11 are each provided with eyes 12, 13 at the top and bottom thereof, respectively, and the pin 9 extends through the upper eyes in the links, thus securing the links to the head. 70 We prefer that the links 10, 11 shall be forged from a solid bar of metal with the eyes 12, 13 formed in both ends thereof. An elevator 14 of any usual and well-known design is mounted between the links 10, 11 at 75 the bottom thereof, and the eyes 13 in said links extend over trunnions 15, 15 projecting from the elevator.

A swivel 16 of usual and well-known design has secured thereto a yoke 17. The 80 bottom of the yoke 17 is widened into a foot 18, which foot bears against cap screws 19, 19 in the swivel, the purpose of this construction being to prevent the tilting of the yoke. A heavy elongated pin 20 is screwed 85 into the yoke 17 preferably with left-hand threads, although any other suitable coupling arrangement may be provided. A head 21 is formed on the top of the pin 20 and the elevator 14 rests against the head 21, 90 as shown in Figure 1.

When the pipe is being raised or lowered in the well if the swivel 16 and yoke would not rotate freely, the pin 20 would tend to rotate in the elevator. To prevent this, we 95 provide a latch 22 which is pivotally mounted in the head 21 and a spring 23 bears against a plate 24, which plate bears against the latch 22 to hold said latch in extended position so that it will bear against either 100

of the links 10, 11 and thus prevent rotation of the pin.

For certain operations it is necessary to prevent the rotation of the pin 3 in the collar 2, and during this time we provide a bar 25 5 which is slidably mounted on the bale 1 and when free rests between lugs 26 formed on top of the bearing 6. When it is desired, to permit swivelling of the collar, a hook 27 secured to a clamp 28 engages an eye 29 on 10 the bar, thus holding it up out of engagement with the lugs on the bearing.

Having described our invention, we claim:

15 A rotary swivel adapted to be supported by an elevator comprising a yoke pivotally secured to the swivel, a pin therefor rising from the yoke, a head formed on the upper end of said pin against which the elevator is adapted to bear, a stop pin pivotally mounted in the head said stop pin engaging 20 the yoke to prevent rotation of the swivel, a plate in the head adapted to press against said last named pin, and spring means urging said plate against the last named pin.

25 In testimony whereof, we affix our signatures.

HERBERT H. HASTINGS.
JOHN H. SWAIN.
